Company, Hartford, Conn., as trustee

Application February 15, 1949, Serial No. 76,504
In the Netherlands April 26, 1948

9 Claims. (Cl. 177—311)

1

This invention relates to a circuit-arrangement by which an electric signalling system, more particularly an automatic telephone system, is protected automatically.

In such systems it is customary to connect the subscribers, divided into groups, to a common voltage supply and to protect the supply against short-circuits by separate fuses provided in the various groups. The groups are divided into sub-groups in the same manner, and the sub-groups may, for example, be further divided into racks which, in turn, may be divided into selectors with associated relays. In each next following division stage the fuses used are smaller than in the previous stage. The groups and sub-groups are usually protected by so-called power current fuses, whereas feeble current fuses are used in the further division stages. The feeble current fuses may be provided with an alarm contact which is closed upon blowing of the fuse, due to which an alarm device is operated and an alarm lamp is lit for indicating and localizing the defect.

In conventional circuit arrangements a blown power current fuse is signalized by means of an alarm relay which is supplied with current via the fuse in question and is normally energized. As soon as the fuse or a fuse in a preceding division stage is blown, the relay is de-energized and alarm is given.

The conventional safety arrangements are not very effective. In practice, it repeatedly occurs upon overloading that a feeble current fuse does not melt immediately, due to which a less sensitive power current fuse might be blown earlier than a feeble current fuse so that the number of user groups disturbed would be greater than is necessary. Furthermore, a fuse may finally be blown after continued loads.

In the majority of cases a short-circuit occurring will be of a very short duration. For instance, a dropping wire may cause a wrong contact to be made during operations in the exchange. In this event a short-circuit occurs, due to which one or more fuses may be blown, but the next instant the short-circuit is again removed. If a voltage were again present at this instant the telephone traffic could again proceed normally.

The present invention meets these disadvantages and it exhibits the feature that at least one of the fuses is shunted by a circuit comprising the series-connection of an alarm relay and a fuse.

By this expedient it is achieved that, if the first-mentioned fuse is blown, the subscribers sup-

2

plied via the fuse may still receive current through the series-connection of the alarm relay and the second fuse, by which the alarm relay is energized. In the event of a short-circuit of short duration the second fuse will quite likely remain intact so that the telephone traffic may proceed normally.

In order that the invention may be clearly understood and readily carried into effect it will 10 now be explained more fully with reference to the accompanying drawing, which represents diagrammatically the supply portion of a telephone exchange.

The subscribers supplied by the common battery B_a are divided into a number of main groups, of which only groups A and B are shown in the drawing. Each main group is subdivided into a number of sub-groups (a, b) and each sub-group is divided in the same manner into 20 racks which, in turn, are divided into subscribers per selector. At every sub-division the supply current is split up into a number of branches which are protected by separate fuses.

The main groups A and B are fed via power 25 current fuses S_A and S_B respectively of, say, 15 amps, one end of these fuses being connected to the negative terminal of battery B_a . The other ends of the fuses are each connected through the series-connection of a fuse (S^{1A} and S^{1B} respectively) and a resistance (R_A and R_B respectively) to one end of a winding H_{A1} of an alarm relay H_A which is common to the main groups A and B. The other end of the winding is connected, through a power current fuse of, say, 20 amperes, 30 to the common ends of the fuses S_A and S_B and to the negative terminal of the battery.

The resistance of the relay winding in series with R_A or R_B has a high value with respect to the resistance of the fuses S_A and S_B , so that only 35 a small fraction of the feed currents of main groups A and B traverses the winding H_{A1} . This fraction is further reduced, since the winding H_{A1} is shunted by a resistance R_{AB} .

If the fuse S_A is blown, the main group A is 40 supplied with current via the by-path constituted by the fuse S_{AB} , the parallel-connection of winding H_{A1} and resistance R_{AB} , resistance R_A and fuse S^{1A} . At first, the supply current mainly traverses R_{AB} only, since the current traversing 45 the relay winding does not directly attain its full value due to self-induction. The resistance R_B has a high value with respect to the resistance of the parallel-connection of the winding and R_{AB} , so that only a small part of the supply current of main group A traverses the fuse S_B .

Consequently, the latter is not appreciably loaded additionally. The same may be achieved by substituting rectifiers for the resistances R_A and R_B .

The relay HA is now energized and completes by way of its make contact HA₁, the second winding HA₂ and the feeble current fuse S₁, a holding circuit for itself, and at the same time the alarm lamp L₁ is lit to indicate the group in which the defect occurs. Furthermore, an acoustic alarm device is made operative by way of contacts (not represented).

If the blowing of S_A is due to a short-circuit of short duration, delayed blowing of a feeble current fuse or continued heavy loads of the fuse, the fuse S_{1A} need not be blown after the fuse S_A has melted, and group A may be further supplied without interruption of the telephone traffic.

In the event of a continued short-circuit, S_{1A} will naturally also be blown and group A no longer passes current. Prior to this, however, the alarm relay operates.

In the circuit-arrangement represented the defect signalization of a power current fuse in the main groups is catered for by an alarm relay. Naturally, each of these relays may alternatively operate more than two main groups.

The same circuit-arrangement is used for protecting the sub-groups. Thus, for instance, an alarm relay is added to the sub-groups *a* and *b* of main group A.

The feed circuits of the holding windings of the alarm relays of main- and sub-groups comprise feeble current fuses S₁ and S₂ respectively of, say, 1 amp. These fuses are furnished with an alarm contact S₁₁ and S₁₂ respectively which is closed when the fuse is blown. If fuse S₂ is blown, a circuit from earth, make contact S₂₂, resistance R₂, winding HA₂ of the alarm relay of a main group, feeble current fuse S₁ to the negative terminal of the battery, is completed by the closure of contact S₁₂. Owing to this, the relay HA is energized and the alarm device becomes operative. To localize the defect one or more alarm lamps L₂ (which may be fitted to several division panels) may be lit. The resistances R₁ and R₂ are chosen to be such that the lamp L₁ does not blink on closing S₁₂.

Similarly, a defective fuse S₁, due to which contact S₁₁ is closed, is signalized by means of the alarm relay HA of a sub-group.

What I claim is:

1. In an electric signalling system, a supply line including a main fuse, a voltage source connected to said line, and an alarm circuit coupled to said fuse, said circuit including a relay having an energization winding and a switch actuated thereby, an auxiliary fuse connected in series with said winding across said main fuse whereby in the event said main fuse blows, the voltage is supplied to said line through said auxiliary fuse and said winding, thereby energizing said winding, and means responsive to the actuation of said switch to produce an alarm indication.

2. An arrangement, as set forth in claim 1, wherein said relay further includes a holding winding connected through said switch to said source whereby upon actuation of said switch said holding winding is energized and retains said switch in its operative position.

3. An arrangement, as set forth in claim 1, wherein said indicating means is constituted by an incandescent device connected in series with said switch to said source.

4. In an electric signalling system, a plurality of supply lines each including a main fuse, one of the ends of the main fuses in said lines being interconnected, a common voltage source connected through said interconnection to each of said lines, and an alarm circuit coupled to two of said lines and including a relay having an energization winding and a switch actuated thereby, first and second resistances, an auxiliary fuse connected in series with said winding and the first resistance across the main fuse in one of the two lines, said auxiliary fuse being also connected in series with said winding and said second resistance across the main fuse in the other of said two lines, and means responsive to the actuation of said switch to produce an alarm indication.

5. In an electric signalling system, a plurality of supply lines each including a main fuse, a common voltage source connected to each of said lines, and an alarm circuit coupled to two of said lines and including a relay having an energization winding, a switch actuated thereby and a holding winding, first and second resistances, an auxiliary fuse connected through said energization winding and said first resistance across the main fuse in one of said two lines, said auxiliary fuse being connected through said energization winding and said second resistance across the main fuse in the other of said two lines, said holding winding being connected through said switch to said voltage source, and a light indicator connected through said switch to said voltage source.

6. An arrangement, as set forth in claim 5, further including a resistor shunted across said energization winding.

7. An arrangement, as set forth in claim 6, wherein said auxiliary fuses possess a higher power rating than said main fuses.

8. An arrangement, as set forth in claim 7, further including a pair of additional fuses interposed between said main fuses in the two lines and said first and second resistances, respectively.

9. In an electric signalling system, a plurality of supply lines each including a main fuse, a common voltage source connected to each of said lines, and an alarm circuit coupled to two of said lines and including a relay having an energization winding, a switch actuated thereby and a holding winding, first and second rectifiers, an auxiliary fuse connected through said energization winding and said first rectifier across the main fuse in one of said two lines, said auxiliary fuse being connected through said energization winding and said second rectifier across the main fuse in the other of said two lines, said holding winding being connected through said switch to said voltage source, and a light indicator connected through said switch to said voltage source.
